[57] CLAIM

The ornamental design for a manifold for use with dual pressure sensor units, as shown and described.

DESCRIPTION

FIG. 1 is a perspective, front view of the manifold for use with dual pressure sensor units of the present invention; FIG. 2 is a top, planar view of the manifold for use with dual pressure sensor units of the present invention; FIG. 3 is a rear, elevational view of the manifold for use with dual pressure sensor units of the present invention; FIG. 4 is a bottom, planar view of the manifold for use with dual pressure sensor units of the present invention; FIG. 5 is a side, elevational view of one side of the manifold for use with dual pressure sensor units of the present invention; FIG. 6 is a side, elevational view of the other side of the manifold for use with dual pressure sensor units of the present invention; and, FIG. 7 is a front, elevational view of the manifold for use with dual pressure sensor units of the present invention.
